UNITED STATES PATENT OFFICE.

JAMES DRAHONOVSKY, OF MILWAUKEE, WISCONSIN.

TIMER FOR INTERNAL-COMBUSTION ENGINES.

Application filed June 22, 1923. Serial No. 646,996.

My invention relates to a simplification of the construction of the timers for internal combustion engines disclosed in my prior applications, Serial No. 635,668, filed April 30, 5 1923, and Serial No. 640,862, filed May 23, 1923, and is designed for accomplishing the same purposes.

The present invention resides in a timer of exceedingly simple and economical construction, the details of which will now be set forth, and the novelty thereof pointed out in the appended claims.

In the accompanying drawing:

Figure 1 is a longitudinal sectional view 15 taken on the line 1—1, Figure 2, showing the construction of my simplified timer.

Fig. 2 is a front elevation, looking from the left of Figure 1, some of the parts being broken out in the interest of clearness.

20 The numeral 10 indicates the frame in which is journaled the timer shaft 11, upon the reduced forward end of which the sleeve 12 of the brush is mounted, such sleeve being held so as to rotate with the shaft by means 25 of a pin which passes through the sleeve and enters a hole in the said shaft. A ferrule 13 covers the head of the pin and is held in position upon the shaft by means of a nut 14, threaded upon the end of the shaft, all as 30 usual in my prior constructions.

25 The casing 15 for the timer may be formed as a stamping, it being provided with an enlarged central portion 16 forming a cavity in which the end of the shaft 11 is received. 35 A ring 17, provided with a circumferential interior shoulder 18, rests in the annular seat 19 formed on the frame 10. The cylindrical web 20 of the casing 15 is adapted to be nested within the ring 17 and rest upon 40 the circumferential flange 18, the parts being held in the positions described by spring pressure of the finger 21.

45 The commutator used in the present invention is of novel form, it being comprised of an annular body 22 which may be approximately square in cross section. A suitable number of projections 23 form integrally with the commutator 22 extend at one side thereof, and are arranged in corresponding 50 openings in the bottom of the casing 15. The annular commutator rests upon the circumferential shoulder 18 of the ring 17 and the projections 23 may be formed with shoulders 24 to bear against the material of 55 the casing in the vicinity of the holes therein, so as to retain the commutator in an ap-

proximately fixed position within the casing at all times. The shoulders 24 on the lateral projections 23 of the commutator form distance pieces which cause the commutator to retain its seat upon the ring 18, but it is obvious that other means between the casing and the commutator ring may be employed for the same purpose. While the said shoulders 24 are shown, it is apparent 65 that they are not essential to the practice of my invention.

In forming the annulus 23 of the commutator the plugs 25 and the connected binding posts 26 are secured in the mould, 70 the posts 26 being positioned so as to have a central location with respect to the projections 23 as the latter are formed as an integral part of the commutator ring 22. From the construction described it will be 75 seen that the electrical connections are thoroughly insulated, and that contact can be made only with the faces of the plugs 25 which are exposed and stand flush with the interior surface of the ring forming the commutator and that the current conducting wires are connected to the posts 26 exteriorly 80 of the casing.

The sleeve 12 mounted upon the timer shaft is provided with a tubular arm 27, in 85 which is mounted for radial movement a brush 28, actuated outwardly into contact with the plugs 25 by means of an expansion spring 29 confined between the sleeve and the brush. The tubular arm 27 is slotted, as 90 at 30, so as to permit movement of a pin 31 attached to the brush 28, the pin serving to retain the brush within the sleeve 27. The spring 28 acts to hold the brush in contact with the plugs during the rotation of the 95 brush, the pressure thereof being sufficient to cause a good contact to be made between the parts. I have shown the brush 28 as formed as a shell in the hollow of which the spring 29 is received, the shell being rounded 100 at its outer and closed end for easy movement over the inner surface of the commutator.

The casing 15 is provided with a projection 32, to which a connection 33 is attached, 105 so that the casing may be given a slight movement of rotation in advancing or retarding the spark.

The construction set forth is simple and very economical in manufacture. Its simplicity adds greatly to the ease with which 110 the parts may be assembled.

Having thus described my invention, what I claim and desire to secure by Letters Patent of the United States, is:

1. A timer for internal combustion engines comprising a rotating shaft and a radially movable brush thereon, a casing provided with openings paralleling the shaft, and a commutator ring located within the casing and provided interiorly with contacts for the brush lateral projections extending through the said openings to support the ring. 35
2. A timer for internal combustion engines comprising a rotating shaft, a tubular sleeve mounted upon the said shaft and carrying a tubular arm extending radially of the shaft, a spring pressed brush mounted in the said tubular arm for radial movement with respect to the shaft, a casing provided with axially parallel openings, and a commutator ring having plugs exposed upon its inner surface and having lateral extensions disposed in the openings by which it is supported in the path of movement of the radially movable brush, to effect contact in the rotative movement of the brush with the shaft. 40
3. A timer for internal combustion engines comprising a frame, a rotating shaft journaled therein, an internally flanged ring seated upon the frame, a commutator ring, 45 contact plugs exposed upon its inner face resting upon the flange, a brush carried by the shaft and adapted to contact with the plugs of the ring, and a casing provided with openings paralleling the said shaft covering the commutator, the said commutator ring being provided with integrally formed lateral extensions passing through said openings in the casing. 50
4. As an article of manufacture, a commutator ring for internal combustion engines having contact plugs imbedded therein and exposed interiorly for radial contact, and provided with lateral extensions in which are embedded binding posts connected to the said plugs, the said lateral extensions forming supports for the said ring. 55
5. A timer for internal combustion engines comprising a ring provided with an internal flange, a commutator ring resting upon the said flange and provided with integral lateral extensions, a casing nested in the said ring and provided with openings for the reception of the said lateral extensions, and means between the said casing and the commutator ring for holding the ring in position upon the said internal flange. 55

In testimony whereof, I have signed my name at Milwaukee, this 16th day of June, 1923.

JAMES DRAHONOVSKY.
